(57) **CLAIM**

The ornamental design for a track slide and wear plug assembly, as shown and described.

DESCRIPTION

FIG. 1 is a front perspective view of a track slide and wear plug assembly illustrating my new design; and

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

In the above-referenced drawings, the broken lines illustrate portions of the article which form no part of the claimed design and are merely environment.
